(57) **CLAIM**

The ornamental design for a swivel chair bearing, as shown and described.

DESCRIPTION

FIG. 1 is a front perspective view of the present invention positioned on a chair.

FIG. 2 is a front perspective view of the swivel chair bearing shown in FIG. 1.

FIG. 3 is a top view of the swivel chair bearing shown in FIG. 1.

FIG. 4 is a bottom view of the swivel chair bearing shown in FIG. 1.

FIG. 5 is a right side view of the swivel chair bearing shown in FIG. 1.

FIG. 6 is left side view of the swivel chair bearing shown in FIG. 1.

FIG. 7 is a front view of the swivel chair bearing shown in FIG. 1; and,

FIG. 8 is a rear view of the swivel chair bearing shown in FIG. 1.

The claimed design and illustrations shown in the drawings depict a swivel chair bearing.

The dash dash broken lines shown in FIGS. 1-7 are included for the purpose of illustrating an environment only and form no part of the claimed design.

1 Claim, 6 Drawing Sheets
